UNITED STATES PATENT OFFICE.

GEORGE W. SCOTT, OF TROY, OHIO, ASSIGNOR, BY MESNE ASSIGNMENTS, TO THE HORTON COMPANY, OF CLEVELAND, OHIO, A CORPORATION OF OHIO.

VEHICLE-TOP.

1,223,429.

Specification of Letters Patent.

Patented Apr. 24, 1917.

Application filed January 8, 1915. Serial No. 1,142.

To all whom it may concern:

Be it known that I, GEORGE W. SCOTT, a citizen of the United States, residing at Troy, in the county of Miami and State of Ohio, have invented certain new and useful Improvements in Vehicle-Tops, of which the following is a specification.

My invention relates to improvements in vehicle tops and especially to that type known as "one man" tops particularly adapted for automobiles. The invention more especially relates to the manner of jointing and supporting the front horizontally arranged bow.

The objects of this invention are to simplify the construction of tops of the character referred to by eliminating certain supporting braces heretofore employed for stiffening the front horizontal bow to provide for greater facility, convenience and quickness of operation in connection with the folding and locking or extension and locking of the two parts of the front horizontal bows, and to also provide a construction which will relieve the covering of the top from strains to which it has been subjected in prior structures when in raised position.

For the attainment of the above objects the invention consists of a joint or means of connection between the two foldably related parts of the front horizontal bow having certain novel and special features of structure, relation and arrangement which will be pointed out in detail as the description proceeds.

In the accompanying drawing,—

Figure 1 is a side view of a portion of the body of an automobile showing a top thereon embodying my improvement, a portion of the covering of the top being broken away.

Fig. 2 is a perspective view of one member of the joint in the horizontal bow which I employ in carrying out my invention.

Fig. 3 is a perspective view of the other member of the joint.

Fig. 4 is a transverse section taken through the pivotal point of the joint, the bow member being omitted.

Like parts are represented by similar characters of reference in the several views.

In the said drawings, 1 and 2 represent, respectively, the rear bows of the top which are connected to the rear portion of the body 3 in the usual way. The forwardly extending horizontal bow is formed in two

parts in the ordinary way, represented, respectively by 4 and 5; the forward part of the bow being detachably connected to the wind shield 6 in the usual way. As is usual, the forward portion 4 has an upwardly and rearwardly extending bow, shown in dotted lines at 7, to support the forward portion of the top covering, 8, the rear portion of the covering being supported by the rear bows 1 and 2.

As is common in tops of this type, the members of the forwardly-extending horizontal bow are hinged together to permit the folding of the bow when the top is lowered; the rear member 5 being hinged to the bow 1, as at 9, so that it may be folded parallel with said bow so as to permit the bows 1 and 2 and the forward portion 4 of the horizontal bow to lie in substantially the same plane in folded position. Heretofore an ordinary hinge joint has been provided between the two members 4 and 5, adapted to break downwardly under pressure, and the material forming the top covering, together with braces of various descriptions, have been relied upon to prevent the joint from breaking when the top is up. In order to relieve the covering from this strain and to obviate the use of the braces, I employ a joint which may be locked so as to render the horizontal bow rigid and self-supporting, it being necessary to unlock the joint before the bow can be broken.

One of these joints is of course located on each side of the top, but as they are constructed exactly alike, but one will be described.

The members of the joint are represented, respectively, by 10 and 11, and have bearing against one another for rotatable movement about a common central axis. Each of said members is of circular form and provided with the usual tapering shank 12 by which connection is made to the bow members in the usual way. The shanks extend beyond the peripheries of the circular joint members and terminate at points in line with the vertical and horizontal centers thereof so as to provide shoulders 12^a which abut in the extended relation of the parts 4 and 5 and other shoulders 12^b which abut in the folded relation of said parts, the shoulders 12^a and 12^b thereby providing stops for limiting the relative pivotal movement of the parts 4 and 5 in connection with the extension or folding

thereof. The member 10 has two diametrical opposite recesses 13, and the member 11 is also provided with similar diametrical opposite recesses 14. In the construction disclosed, the parts 4 and 5 have their folding and extensible movements through a range of 180° ; and in consideration of this fact, each recess occupies one-fourth the face of its member and the face portions 15 and 16 which intervene between the respective recesses similarly each occupy one-fourth of the faces of their respective members. The recesses are so positioned on the respective members that when the bow members 4 and 5 are in a straight line relatively to each other, the face portions 15 and 16, respectively of the hinge members will coincide with the recesses so as to enter the same and form an interlocking engagement between the hinge members. The face portions 15 and 16 are plain or smooth-surfaced and during the folding or extension of the bow occupy an overlying relation in which they are freely movable counter to one another.

25 A screwthreaded bolt 17, having a nut 18, extends through apertures 19 and 20 in the respective hinged members to hold them in interengaged position; one of the apertures such as 20, being formed square to receive a squared portion of the bolt to prevent the bolt from turning in locking or unlocking the joint.

When the parts 4 and 5 are to be moved into extended or folded relation, the nut 18 is backed off sufficiently to permit of the required lateral separation of the members 10 and 11 and the parts 4 and 5 are freely moved in the desired direction, their movement in the embodiment disclosed being arrested by the stops 12^a or 12^b, as the case may be. When the parts 4 and 5 are thus brought into their fully extended or folded relation, the face portions 15 and 16 will register with the respective recesses 14 and 13, at which time the members 10 and 11 are moved together so as to establish interengagement of the registering face portions and recesses and the nut 18 is tightened to positively hold said members in their interengaged relation.

50 From the foregoing description it will be apparent that the form of the joint between the parts 4 and 5 bears a definite relation to the range of folding or extending movement of said parts; that is to say, the joint is so constructed that its members will interlock in either the fully extended or the fully folded positions of the parts of the front horizontal bow but will not and cannot interlock in any intermediate position. A two-fold advantage is thereby secured in that the full pivotal movements of the parts of the bow and the inter-engagement of the

members of the joint at the completion of such pivotal movements may be effected with ease and facility and the locking projections or face portions, as 15 and 16, may, without any undue enlargement of the joint, be made relatively large or heavy, and, therefore, of strength amply sufficient to rigidly sustain the weight of the front part 4 and of the canopy top.

55 By this construction it will be seen that in effect a rigid horizontal bow is provided supported at the front and rear by the wind shield and rear bow, respectively, that all strain from the top covering is removed, and that no additional braces are required to hold the bow in supporting position. By having the members 10 and 11 of the joint formed of 80 circular or disk shape additional strength is given to the joint, so that the joints will be as strong at least as any other part of the bow.

Having thus described my invention, I claim:—

1. In an automobile vehicle top, a front horizontal bow having connected front and rear parts foldable and extensible through a definite range of movement, and a joint between said parts comprising laterally separable companion members, one carried by each of said parts, said members having a rotatable bearing against one another and being provided with inter-matching projections and recesses formed and arranged to operatively inter-engage in either the fully extended or fully folded position of said parts but to be incapable of inter-engagement in any intermediate position of said parts.

2. In an automobile vehicle top, a front horizontal bow having connected front and rear parts foldable and extensible through a half circular range, and a joint between said parts comprising laterally separable companion members, one carried by each of said parts, said members having a rotatable bearing against one another and being provided with inter-matching projections and recesses and with shoulders which abut upon the completion of the folding or extension of said front and rear parts and thereby limit the folding or extensible movements of said parts, the projections and recesses of each member being arranged in diametrically opposite relation and having an area of one-fourth of a circle, the projections being plain or smooth-surfaced, as and for the purpose set forth.

120 In testimony whereof, I have hereunto set my hand this 28th day of December, 1914.

GEORGE W. SCOTT.
